UNITED STATES PATENT OFFICE

2,421,604

METHOD OF APPLYING BACKSTAYS TO
SHOE UPPERSCharles Chester Eaton, Brockton, Mass., assignor
to Charles A. Eaton Company, Brockton, Mass.,
a corporation of Massachusetts

Application December 22, 1944, Serial No. 569,353

2 Claims. (Cl. 12—146)

1

The present invention relates to shoes provided with backstays which cover the vertical seam at the rear end of the upper. Its objects are to facilitate the application of backstays and the lasting of shoe uppers, and to give a better fit and appearance at the heel end of the shoe upper.

In the making of shoe uppers, the rear edges of those parts of the upper which form the quarter of the shoe are cut with a convex curvature and stitched together. The convexity thereby produced in the united parts of the quarter enables that part of the upper to conform to the last and causes it to fit well around the spheroidal curvature of the wearer's heel when incorporated in a finished shoe. But it also causes difficulty in the application of backstays which extend throughout the height of the upper from the top edge thereof to the heel seat.

Heretofore in the making of shoes provided with backstays of this character it has been the universal practice to stitch the backstay first along one of its edges to the upper, holding it as nearly as possible in symmetrical relation to the back seam, and then stitch the opposite edge to the upper. This has been a difficult operation, requiring much skill, great care and considerable muscular effort on the part of the operator to hold the backstay firmly in the correct position and make it as smooth as possible. These difficulties are particularly pronounced in the case of backstays with curved edges and varying widths; although they are present in all cases. Even with the greatest care puckers or wrinkles are usually formed either in the upper leather beneath the backstay or at one or both margins of the backstay on the outside of the shoe. When wrinkles are formed on the inside of the upper they impair the fit and cause discomfort to the wearer, and when on the outside they detract from the appearance of the shoe and decrease the durability of the attachment of the backstay. Too frequently also the wrinkling is so bad that the value of the upper is seriously impaired and it can be used only in a shoe of lower price than that of the shoe for which the upper was intended.

The purpose and accomplishment of my invention is to overcome these difficulties and produce better fitting and better looking shoe uppers. The invention consists in the new procedure described in the following specification and in the new characteristics of shoe uppers and shoes resulting from the practice of this procedure.

The accompanying drawings illustrate the principles of the invention, and therein,

Fig. 1 is a side elevation, and Fig. 2 a rear eleva-

2

tion, of a shoe having a backstay applied to the upper in the manner of this invention;

Fig. 3 is a perspective view of the heel end of an upper after the pieces which form the quarter thereof have been stitched together at the back seam and before application of the backstay or the lining;

Fig. 4 is a perspective view of the backstay shown in Figs. 1 and 2;

Fig. 5 is a perspective view showing the upper and backstay in the condition which follows the first step of the attaching procedure;

Fig. 6 is a cross section of the same taken on line 6—6 of Fig. 5;

Fig. 7 is a vertical section through the upper and backstay at one side of the back seam taken approximately on the line 7—7 of Fig. 6;

Fig. 8 is a section similar to Fig. 6 showing the results of the final steps of securing the backstay to the upper.

Like reference characters designate the same parts wherever they occur in all the figures.

Although the illustration in these drawings shows the invention applied to a low quarter shoe, this is not intended as a limitation of the invention to shoes of that category. On the contrary, it is applicable to shoe uppers with high tops as well.

In the drawings, *a* and *b* represent the rear ends of the two pieces of leather or other material which form the quarter of the shoe. Their rear extremities are cut on a convex curve, as usual, and stitched together by any suitable kind of seam, that here shown at *c* being a butt seam connected by zigzag stitches, which is one of the standard types of seam for this part of the work. The backstay is shown at *d*. The one here illustrated is of varying width, having a narrow portion or neck between wider ends, and its side edges being curved with reversed curvature and being non parallel in most of their length.

The novelty of the present invention consists in the procedure of attaching the backstay to the upper and the manner of attachment resulting therefrom. The backstay is first attached by two rows of stitches, or seams, *e* and *f*, located at opposite sides of the back seam *c* and preferably as nearly parallel to and equidistant from that seam as possible. By way of general statement it may be said that the rows of stitches *e* and *f* are parallel to the back seam and equally distant from it. This does not mean that the parallelism and equality of distance must be exact within the closest possible limits, but includes variations from exactness within reasonable limits.

Preferably the two rows of stitches *e* and *f* are applied simultaneously by a double needle sewing machine. Although this is not an absolute essential of the invention, yet it is practically necessary in the interest of economy of time and effort by the operator. It also insures absolute parallelism of the two rows of stitches and reduces the element of care on the part of the operator to only that which will insure that the stitches are on opposite sides of the back seam and substantially parallel to and equally distant from it.

In this way the back seam is laid smoothly over the convex curve of the quarter and is securely and immovably attached to it. Then the margins of the backstay are separately and in succession made fast to the upper by stitches placed near to the edges of the backstay and following the curvatures of such edges. Preferably two rows of stitches are set near each edge by a double needle sewing machine of which the two needles are close together; but a single row may be applied instead. The utility of the double row is that it increases the security and durability of the attachment. Fig. 8 shows at *g* two rows of final stitches adjacent to one edge of the backstay, and at *h* two similar rows of stitches adjacent to the opposite edge. Thereafter the upper is assembled with a lining and other findings, placed on a last, and incorporated into a finished shoe by any suitable method of shoe making.

The new procedure here involved has numerous advantages over the old. It simplifies the operation of attaching a backstay, causes the appearance and fit of the upper to be improved, and avoids substantially all of the loss and waste due to unsatisfactory placement of backstays according to the old practice. As previously pointed out, the stitching of the parallel seams *e* and *f* is a simple operation easy to perform correctly. Thereafter, each of the edge stitching operations is equally simple and easily performed. They are preferably started at the upper edge of the upper. In progressing thence toward the lower edge, the presser foot of the sewing machine smooths the backstay and presses out any wrinkles that may tend to form due to the transverse curvature then imposed on the backstay. Due to the initial attachment of the backstay along its middle zone, the widths between the seam *e* and the nearer edge of the stay are equal to the widths between the seam *f* and the other edge. Hence the stitching down of one edge does not increase the tendency for wrinkles and

puckles to form in either the stay or the quarter piece when the other edge is stitched down, as is the case with the old method. This preserves the curves at the heel end of the upper just as designed by the pattern maker. These improvements are manifest in the upper at the time of lasting by the way in which it better fits the heel end of the last, and in the finished shoe by making a better fitting and more comfortable shoe, free from interior wrinkles or ridges and having a better appearance due to the smooth accommodation of the backstay to the contours of the upper.

What I claim and desire to secure by Letters Patent is:

1. The method of connecting a backstay of single thickness to a shoe upper which has quarter pieces with convex edges sewed together, comprising fastening the longitudinal middle zone of the backstay to the upper by rows of stitches near to said seam at opposite sides thereof, and then stitching the edge portions of the backstay to the upper progressively from the top edge to the bottom edge of the upper by the operation of a sewing machine.

2. The method of connecting a backstay to a shoe upper which has quarter pieces with convex edges sewed together, which comprises fastening the longitudinal middle zone of the backstay to the upper by running simultaneously two parallel lines of stitching along said zone and near to the upper seam at opposite sides thereof, and thereafter stitching the edge portions of the backstay to the upper.
